UNITED STATES PATENT OFFICE.

JOHN T. QUIGLEY, OF BOSTON, MASSACHUSETTS, ASSIGNOR TO THE COSTMETER COMPANY, OF BOSTON, MASSACHUSETTS, A CORPORATION OF CALIFORNIA.

FEEDING DEVICE.

1,156,037.

Specification of Letters Patent.

Patented Oct. 5, 1915.

Original application filed November 8, 1913, Serial No. 799,988. Divided and this application filed November 11, 1913. Serial No. 800,424.

To all whom it may concern:

Be it known that I, JOHN T. QUIGLEY, a citizen of the United States, and a resident of Boston, county of Suffolk, State of Massachusetts, (whose post-office address is 9 Norway street, Boston, Massachusetts,) have invented an Improvement in Feeding Devices, of which the following description, in connection with the accompanying drawings, 10 is a specification, like characters on the drawings representing like parts.

This invention relates to devices for feeding or advancing paper or other record sheets in continuous strip form where such feeding or advance is required to be carried on accurately and positively.

The invention is applicable to various uses, but more particularly to recording and calculating machines where it is required to 20 advance a paper record strip at a positive and definite rate, as for example, a rate proportional to elapsed time.

The present invention provides means whereby the feeding of such a strip may be effected through a suitable carrier without the slippage or creeping of the strip relative to the carrier, and whereby the movement of the strip may at all times be exactly proportional to the movement of the carrier.

30 The invention will be best understood by reference to the following description when taken in connection with the accompanying illustration of one specific embodiment thereof, while its scope will be more particularly 35 pointed out in the appended claims.

In the drawings: Figure 1 is a section in elevation showing strip-feeding mechanism wherein there are employed feeding devices for feeding two continuous strips of paper tape to suitable printing mechanism; Fig. 2 is a side elevation of one of the tape-feeding 40 drums or carriers. Fig. 3 is a transverse section in elevation showing one of the tape feeding drums and its guard; and Fig. 4 is a plan view of a portion of a paper strip or tape.

Referring to the drawings and to the embodiment of the invention which is therein shown for illustrative purposes, two continuous paper tapes or strips 1 and 2 are shown supplied from rolls 3 and 4 mounted to turn upon the studs 5 and 6, respectively. The tape 2 passes from its roll 4 under the guide roll 7 and over the roll 8 and thence

into superposed relation to the tape 1, which latter passes from its roll 3 under the guide roll 9. In this relation they are advanced together past suitable fixed printing or recording devices. The construction of the recording devices is not material to the present invention, and the same are herein typified by the printing plate 10 which may carry raised printing characters and rests transversely the tapes on the bed plate 11 the latter supported by the block 12. Between the printing plate 10 and the lower tape there is arranged transversely the tape an inking ribbon 13, and between the tape 2 and the tape 1 a second transverse inking ribbon 14. A platen or wiper block 15 is provided normally at one side of the tapes and permitting the free feeding movement of the latter, but adapted to be moved with a wiping pressure transversely the tape as may be required to leave the imprint of the printing characters thereon. From the printing mechanism the tape 2 passes about the guide roll 16 and thence to its feeding drum or carrier 17 while the upper tape 1 passes over the feeding roll 18 and thence to 80 its feeding drum or carrier 19. In order to feed the tape a definite, predetermined amount for each revolution of the carrier, the circumference of each tape feeding drum is constructed so as to give the required 85 travel to the tape for each revolution thereof, due allowance being made for the thickness of the tape and the distance from the center of the drum at which the tape is punctured, and provision being had whereby 90 slippage or creeping of the tape on the drum is avoided. To this end it is necessary that the tape should contact with the drum in closely fitting relation and that positive 95 feeding means should be employed. In the present case the tape is fed positively by means of a series of feeding members 20, herein six in number, distributed at equal intervals around the circumference of the drum. While a single series of feeding 100 points might suffice, preferably a double row or series (Fig. 3) is employed, so that they occur in pairs side by side. This not only insures a positive feed, but keeps the tape aligned and prevents it from twisting on the 105 drum.

The feeding members are herein in the form of needles presenting very fine points

projecting through the shell of the drum and above its surface for a sufficient distance only to insure impaling the tape. Herein the inner ends of the needles are fixedly secured to the hub 21 of the drum in tangential relation, so that the points incline slightly forward in the direction of drum rotation in a position securely to grip the tape when impaled. This relation of the feeding points provides for penetration of the tape with the least expenditure of power and the least tendency to disturb the tape on the drum. The relation of the impaling points, however, is such that taken in co-operation with the hereinafter described guard there is no tendency to lift or advance the tape relatively to the drum, the former preserving at all times its close fitting relation to the drum periphery. The number and relation of the feeding points is preferably such that at least two pairs are always engaged with the tape.

To insure the close fitting relation of the tape to the drum and permit the feeding points to impale the tape without lifting it or advancing it on the drum, means is preferably provided, such as the segmental guard 22 fixed relatively to the drum but overlying the tape or the portion thereof where it is wrapped about the drum. As shown in the drawings, the guard is longitudinally grooved at 23 and 24 in the plane of the needle points so that the latter after impaling the paper may travel through the grooves. At the side of each groove, however, the walls of the guard approach very closely to the periphery of the drum, leaving only sufficient room for the paper and a slight additional clearance. To prevent pinching the paper the drum is preferably provided with circumferential grooves 25 directly opposite the three closely fitting portions of the guard and arranged in alternation with the grooves 23 and 24 on the guard. This construction permits the paper to pass freely about the drum and between the drum and the guard and causes it to be impaled by the feeding points without any danger of its buckling or lifting from the drum. The guard 22 also serves the additional function of insuring precisely the same linear distance between successive punctures of the tape, upon which condition depends the accuracy of the feed. In the described form of the invention the tape is punctured at or closely adjacent the tape receiving edge of the guard. This edge is preferably beveled at such an angle that the tape is presented at substantially right angles to the feeding point as the latter moves into a position of puncture. The puncture of the tape at the beveled edge of the guard also provides that successive punctures invariably take place at precisely the same distance from the center of the drum. With

a uniform angle of puncture and a uniform distance from the center of the drum, precisely the same distances between successive feed puncture points will always be had and this will be obtained by reason of the presence of the guard irrespective of the tension which may be maintained upon the paper as it is drawn toward the feed drum. 70

The tape as it leaves the feeding drum passes to any suitable storage receptacle and to prevent any tendency for the tape to cling to the drum, fixed stripping fingers 26 are employed which are provided with beveled ends entering the middle groove 25 and acting to strip the tape from the drum 80 should the former adhere to the latter. The described strip-feeding mechanism may be employed in recording for other machines of any description wherein an accurate and predetermined advance of the paper strip 85 is required. It is particularly advantageous where an accurate feed of the record strip is required proportional to elapsed time. In the illustrative form of the invention two drums 17 and 19 are turned at uniform and predetermined rates proportional to elapsed time by means of clockwork mechanism represented at 27. Herein the rate of feed of the two tapes may be differently adjusted by means of change gearing 90 interposed between the clock-driven shaft 28 and each feeding drum. For this purpose the shaft 28 is provided with two driving gears 29 and 30, the latter driving the drum 19 through the intermediate gear 31 and the 100 driven gear 32, the latter secured to the driving shaft 33 for the feed drum 19. Similarly the gear 29 drives the feed drum 17 through the intermediate gear 34 and the driven gear 35. By this means the two tapes 105 may be made to advance at different rates of speed and the rate of speed of either tape may be varied as required by changing the ratio of the gears 29 and 34 and 30 and 31, respectively. 110

I do not herein claim the recording devices or the combination of the recording devices with the feeding mechanism shown in the illustrative embodiment of my invention, the same being claimed in my copending application Serial No. 799,988. 115

While I have herein shown and described for purposes of illustration one specific form of the invention, it is to be understood that the same may be widely deviated from without departing from the spirit of the invention. 120

I claim—

1. In a feeding and measuring device a sheet feeding member having a sheet feeding surface, fixed impaling members provided with impaling points projecting from said surface and inclined in the direction of movement of the sheet whereby the sheet will be punctured and brought into close 130

contact in unchanging relation to the sheet feeding surface, and means for driving said member.

2. In a mechanism for feeding and measuring a continuous record sheet, a sheet feeding drum having a circumference accurately dimensioned with reference to the intended rate of feed and having fixed impaling members provided with impaling points inclined forwardly in the direction of rotation of the drum, and means for turning the drum.

3. In a mechanism for feeding and measuring a continuous record sheet, a feed drum, means for turning the same, impaling points projecting from the feeding surface of the drum adapted to impale the sheet, and a guard extending for a substantial distance over the feeding surface of the drum to press the sheet into close feeding relation with the surface thereof and the impaling points.

4. In a mechanism for feeding and measuring a continuous record sheet, a feed drum, means for turning the same, impaling points projecting from the surface thereof at a forward inclination with reference to the direction of drum rotation and adapted to impale the sheet, and a guard extending for a substantial distance over the feeding surface of the drum to press the sheet into close feeding relation with the surface thereof and the impaling points.

5. In a mechanism for feeding and measuring a continuous record sheet, the combination with a sheet feeding drum, impaling points projecting from the surface thereof, and a segmental guard plate arranged to press the sheet closely against the drum and provided with one or more grooves to permit the passage of the impaling points.

6. In a mechanism for feeding and measuring a record sheet, the combination with a sheet feeding drum, impaling points projecting from the surface thereof, a segmental guard plate arranged to press the sheet closely against the drum and provided with one or more grooves to permit the passage of

the impaling points, said drum being provided with one or more circumferential grooves alternating with a groove or grooves in the guard plate.

7. In a mechanism for feeding and measuring a record sheet, the combination with a feeding drum of impaling points projecting from the surface thereof, and means extending circumferentially for a substantial distance about the drum for pressing the sheet toward the drum on each side of the impaling points.

8. In a mechanism for feeding and measuring a record sheet, the combination with a feeding drum of impaling points projecting from the surface thereof, and means extending circumferentially for a substantial distance about the drum for pressing the sheet toward the drum on each side of the impaling points, said drum having circumferentially arranged grooves opposite the said pressing means and on each side of the impaling points.

9. In a mechanism for feeding and measuring a continuous record sheet, the combination with a feeding member having a feeding surface determining the rate of feed, impaling points projecting from said surface, and means extending for a substantial distance over the feeding surface for pressing the sheet toward the same about the impaling points.

10. In a mechanism for feeding and measuring a continuous record sheet, a sheet feeding drum having an accurately dimensioned feeding surface, impaling points projecting from said surface, circumferential depressions in the feeding surface of the drum, and means positioned opposite the said depressions for pressing the sheet into closely fitting relation with reference to the said drum.

In testimony whereof, I have signed my name to this specification, in the presence of two subscribing witnesses.

JOHN T. QUIGLEY.
